UNITED STATES PATENT OFFICE.

HERMAN REESSING, OF NEW YORK, N. Y.

DESIGN FOR A JAR.

SPECIFICATION forming part of Design No. 23,923, dated January 1, 1895.

Application filed November 9, 1894. Serial No. 528,353. Term of patent 7 years.

To all whom it may concern:

Be it known that I, HERMAN REESSING, a citizen of the United States, residing in the city, county, and State of New York, have invented and produced a new and original Design for Jars, of which the following is a specification, reference being had to the accompanying drawing, which shows a side elevation of the same.

10 The leading feature of my design consists of a jar provided with a double bead extending around the neck, a bead extending around the base a short distance above the bottom of the jar, such base flaring outwardly from the 15 bead to the bottom, and a single bead extending around the jar a short distance above the lower bead.

15 A is the body and B is the neck of the jar. The body of the jar is circular in contour and 20 tapers gradually at its upper part toward the cylindrical neck.

The neck B is provided with a double bead b, while the base of the body is provided near the bottom with a single bead d, from which the base-portion of the body flares outwardly 25 and downwardly to the bottom thereof. Above the single bead d and at a distance of about one-fourth of the height of the jar, is located a single bead e. The beads or bands which encircle the body and neck of the jar impart 30 an ornamental and characteristic appearance to the jar.

What I claim is—

35 The design for a jar, substantially as shown and described.

In testimony that I claim the foregoing as my invention I have signed my name in presence of two subscribing witnesses.

HERMAN REESSING.
